UNITED STATES PATENT OFFICE

SOL ROTH, OF COLUMBUS, OHIO

DESIGN FOR A CHIP CONTAINER

Application filed February 4, 1933. Serial No. 47,103. Term of patent 7 years.

To all whom it may concern:

Be it known that I, SOL ROTH, a citizen of the United States, residing at Columbus, in the county of Franklin and State of Ohio, have invented a new, original, and ornamental Design for a Chip Container, of which the following is a specification, reference being had to the accompanying drawing, forming part thereof.

The figure is an isometric view of a chip container embodying my design.

I claim:

The ornamental design for a chip container, as shown.

SOL ROTH.
